UNITED STATES PATENT OFFICE.

HARRY M. DOUBLEDAY, OF NEW YORK, N. Y., ASSIGNOR OF THREE-FOURTHS
TO JAMES S. HUMBIRD AND FRANK S. MARR, BOTH OF HARRISBURG,
PA., AND JAMES LYMAN, OF MIDDLEFIELD, CONN.

SYSTEM OF ELECTRIC LIGHTING.

SPECIFICATION forming part of Letters Patent No. 335,060, dated January 26, 1886.

Application filed June 26, 1885. Serial No. 169,825. (No model.)

To all whom it may concern:

Be it known that I, HARRY M. DOUBLEDAY, of New York city, in the county and State of New York, have invented a certain new and 5 useful Improvement in Systems of Electric Lighting, of which the following is a specification.

My invention relates to systems of lighting by electrical incandescence, and more particularly to the supplying of street-lamps from such a system.

The object I have in view is to provide in a simple and efficient manner a separate control of the street-lamps from the central station, so 15 that such street-lamps can be turned off and on from the station, the street-lamps being supplied with current from the same source that supplies the domestic lamps, and the conductors for the domestic lamps being 20 utilized in conveying current for the street-lamps.

The invention consists in the means employed for accomplishing these general objects, and also in details used in the carrying 25 out of these objects practically in connection with a domestic system of electric lighting, to provide for safety for the regulation of the street-lamps independent of the domestic lamps, and for permitting the turning on and 30 off of the street-lamps without noticeably affecting the domestic lamps.

The invention is especially applicable to the Edison three-wire or compensating system, although also applicable to a simple two-wire 35 system, as will be hereinafter pointed out.

In the accompanying drawings, forming a part hereof, Figure 1 is a diagram of parts of an electric-lighting system illustrating my invention. Figs. 2 and 3 are modifications there- 40 of, and Fig. 4 is a further modification.

With reference more particularly to Fig. 1, A represents a central station for a three-wire or compensating system provided with dynamos (not shown) for generating the current connected with the omnibus conductors 45 1 2 3 in the station. From these omnibus conductors extend, as usual, feeders B B', each composed of three conductors, 4 5 6, to sections C

C' of the system. These sections are portions of the domestic mains, each composed of three 50 conductors, 7 8 9, such domestic mains being connected together by intervening domestic mains, as shown by the crossing lines D at the right of Fig. 1, the whole forming a connected system of positive, negative, and neutral or 55 compensating conductors supplied by feeders from the central station. From these domestic mains house-circuits extend, and in these are located domestic incandescent electric lamps a. The domestic system is provided with all 60 the usual appliances for regulation, control, and safety, which it is not thought necessary to describe herein.

For the street-lamps I provide separate and independent single part mains 10 11, connected 65 with the station by single part feeders 12 13. The feeder 12 is connected at station with the positive omnibus conductor 1, while 13 is connected with the negative omnibus wire 3. Street-lamps b are connected between the 70 mains 10 11 and the neutral or compensating conductor 8 of the domestic mains.

Throughout the domestic system, wherever it is desired to place street-lamps, the street-lamp mains will extend. These will be divided into a suitable number of separate independent sections, and as many of the single part feeders 12 13 will be used as there are separate divisions to the street-lamp mains, such feeders being preferably divided between 75 the two sides of the circuit, half of these being connected with the positive omnibus conductor and half with the negative omnibus conductor.

At the central station each street-lamp feeder is provided with a switch, c, for making and breaking the circuit of the street-lamps connected with the particular division of the street-lamp mains supplied by the feeder, and each of such feeders also has an adjustable resistance, R, which may be a wire or lamp resistance located in the station. This resistance is employed for regulating the street-lamps in candle-power; but its principal use is to permit the street-lamps to be thrown into 90 and out of circuit gradually, the resistance be- 95

ing first gradually introduced into the feeder before the switch is opened, and being gradually cut out of the feeder after the switch is closed. The street-lamps being thrown on and off one division at a time, and by the gradual cutting out and in of the resistances, the effect upon the domestic lamps will not be noticeable. Each street-lamp feeder also has a fusible safety-catch, *d*, proportioned to carry to the maximum normal load of the feeder.

Where it is desired to operate street-lamps beyond the limits of the domestic mains, which is often the case, I extend the neutral conductor 8 of the domestic mains by lines 14 15, connected together at their outer ends. Street-lamp mains 16 17 are run parallel to such neutral lines 14 15, and are connected by positive and negative feeders 18 19 with the station, the effect of the full electro-motive force being obtained by this arrangement.

As a modification of the system it is evident that some or all of the street-lamp mains may be connected directly with the station, as shown in Fig. 2. This would be done with mains close to the station and not themselves of great length.

In applying the invention to a simple two-wire domestic system, Fig. 3, the street-lamps will be located between positive and negative 30 street-lamp mains and domestic mains of opposite polarity.

A number of street-lamp mains would preferably be used divided between the two sides of the system, as before explained with reference to the three-wire system.

All of the street-lamp feeders from the station, whether to mains within the limits of the domestic system or beyond, as well as all direct connections of street-lamp mains to stations, 40 will be provided with switches, adjustable resistances, and safety-catches, as before explained.

I prefer in some cases to dispense with the feeders to the street-lamp mains within the limits of the domestic system, and to supply such street-lamp mains from the street-lamp mains outside the limits of the domestic system, the two sets of mains being connected together and the feeders running to the outlying mains only. This arrangement, which is shown in Fig. 4, is desirable, in order to secure the best distribution of the current.

What I claim is—

1. The combination, with a domestic system of lighting by electrical incandescence, of an additional conductor connected independent of the domestic system with one pole of the source of electrical supply at the station, and lamps connected between such additional conductor and a conductor of the domestic system, substantially as set forth.

2. The combination, with a connected system of conductors, incandescent electric lamps connected in multiple arc with such conductors, and a source of electrical energy connected by feeding-circuits with such system of conductors, the whole forming a domestic system

of electric lighting, of one or more additional conductors, incandescent electric lamps connected in multiple arc between such additional conductors and conductors of the domestic system, and one or more separate connections from such additional conductors to the source of supply of the domestic system, substantially as set forth.

3. The combination, with a three-wire or compensating system of electric lighting, of an additional conductor, electric lamps connected between such additional conductor and the neutral or compensating conductor of the system, and a separate connection from such additional conductor to one side of the source of electrical supply, substantially as set forth.

4. The combination, with a domestic system of electric lighting, of street-lamps connected between an additional conductor and a conductor of the domestic system, a separate single part connection from such additional conductor to one side of the source of electrical supply, and an adjustable resistance in such connecting-conductor, substantially as set forth.

5. The combination, with a domestic system of electric lighting, of street-lamps connected between an additional conductor and a conductor of the domestic system, a separate single part connection from such additional conductor to one side of the source of electrical supply, and a circuit making and breaking switch in such connecting-conductor, substantially as set forth.

6. The combination, with a domestic system of electric lighting, of street-lamps connected between an additional conductor and a conductor of the domestic system, a separate single part connection from such additional conductor to one side of the source of electrical supply, and a fusible safety-catch in such connecting-conductor, substantially as set forth.

7. The combination, with a domestic system of electric lighting composed of connected conductors supplied by feeders from a central station, of two or more separate and independent additional conductors, lamps connected between each of such additional conductors and the conductors of the domestic system, and a separate connection from each additional conductor to the source of supply at station, substantially as set forth.

8. The combination, with a domestic system of electric lighting composed of connected conductors supplied by feeders from a central station, of street-lamps arranged in divisions, the lamps of each division being connected between an additional conductor and a conductor of the domestic system, and separate connections from such additional conductors to the source of supply, such connections being made some to one side or pole and some to the other side or pole of the source of supply, substantially as set forth.

9. The combination, with a three-wire or compensating system of electric lighting, of street-lamps arranged in divisions between independent additional conductors and the neu-

tral or compensating conductor of the system, and separate connections from such additional conductors to the source of supply, such connections being made some to one side or pole 5 and some to the other side or pole of the source of supply; substantially as set forth.

10. The combination, with a three - wire or compensating system of electric lighting, of an extension of the neutral conductor beyond the limits of the system, an additional conductor parallel with such extension of the neutral conductor, street-lamps located between such additional conductor and the extension of the neutral conductor, and a separate connection 15 from said additional conductor to the source of supply, substantially as set forth.

11. The combination, with a three - wire or compensating system of electric lighting, of an extension of the neutral conductor beyond the limits of the system, two or more additional conductors parallel with such extension, connections from such additional conductors to opposite sides or poles of the source of supply, and street-lamps located between such additional conductors and said extension of the neutral conductor, substantially as set forth. 20 25

This specification signed and witnessed this 9th day of June, 1885.

HARRY M. DOUBLEDAY.
